UNITED STATES PATENT OFFICE.

JAMES L. BROWNLEE, OF WHEELING, WEST VIRGINIA.

SPRING-CLIP FOR REINFORCING-BARS.

977,704.

Specification of Letters Patent. Patented Dec. 6, 1910.

Application filed June 21, 1909. Serial No. 503,587.

To all whom it may concern:

Be it known that I, JAMES L. BROWNLEE, a citizen of the United States, residing at Wheeling, in the State of West Virginia, have invented a new and useful Spring-Clip for Reinforcing-Bars, of which the following is a specification, reference being had therein to the accompanying drawings.

My invention relates to a new and useful 10 spring clip, and its object is to provide a simple and inexpensive device of this character which will quickly secure reinforcing bars and hold them in their positions during the process of construction.

15 A further object is to provide a spring clip of novel construction that is self locking and does not require the members to be distorted as in other clips of a like nature.

20 A further object is to provide a spring clip of novel construction that can be used in combination in securing reinforcing bars.

25 A further object is to provide a spring clip of novel construction that does not require the use of tools in applying same to the members to be secured or that requires distortion in being removed from the members.

To these ends the invention comprises the 30 novel features of construction and combination more fully hereinafter described.

In the accompanying drawings Figure 1, is a perspective of cross members or bars held in place by the use of my invention. Fig. 2, is a detailed view in perspective of a 35 spring clip showing the central cross groove adapted to receive members or bars that are not of rectangular dimensions. Fig. 3, shows a modified construction, of a spring clip, wherein the central cross groove is constructed for members or bars of rectangular dimensions. Fig. 4, is a side elevation showing a longitudinal member or bar and the end of a cross member or bar held in 40 position by my invention, also the dotted lines show approximately the position of my invention immediately before applying same to the longitudinal member or bar. Fig. 5 is a side elevation, showing one of the extremities or legs of my spring clip 45 resting in position on a member or bar and the diagonally opposite engaging edges 8 and 9.

Like numerals indicate like parts in all the figures of the drawings.

50 The cross members or bars used in concrete construction, such as the members 1

and 2, should be fastened together where they cross each other so as to be free from any movement one upon the other, and it is to provide a spring clip capable of performing this function that I use a blank sheet or plate of steel or other resilient metal from which is struck the spring clip, 3 forming the subject matter of my invention.

The spring clip when first struck is nearly 60 of rectangular dimensions with the edge slots 4, which form recesses, to receive one of the bars. These slots are struck so that their sides are perpendicular to the faces of the clip. This is a very important feature 65 as will be shown later.

Before my spring clip is suited to be applied to the cross members after being struck from a blank sheet or plate of steel it is necessary to crimp the plate so as to form 75 the central cross groove 5, the resilient arms 6 and the legs 7. The central cross groove 5 receives one of the members and partly surrounds same, the resilient arms 6 are to provide levers to allow the legs 7 to spring, and 80 space on each side of the central cross groove so a like clip can be used in combination to interlock the coöperating cross members, and the legs 7 carry edge slots 4, provide means 85 of support for the members should they become displaced and tend to rest upon the form and means by which the spring clip can be placed upon the member.

The legs 7 are crimped so as to stand at or 90 near 45° with the members being secured, as best shown in Fig. 4. The edge slots 4 are slightly larger than the bars being held, and when the clip is sprung into the position shown by the dotted lines in Fig. 4, by grasping the tops of the legs 7 and squeezing them 95 together, the diagonally opposite engaging edges 8 and 9 release their grip and the clip can be removed or replaced at will.

It is to be noted that the resilient arms 6 are crimped so as to join the top sides of the 100 central cross groove 5 with a radius which gives the resilient arms 6 a downward slope. The edge slots 4 are slightly above the resilient arms 6 and tops of the central cross groove 5. These are very important features 105 in my invention. First, the resilient arms 6 having a downward slope from the tops of the central cross groove 5 allow the legs 7 to spring outward and downward when pressure is exerted upon the diagonally opposite engaging edges 8 and 9 by the bar tending to slip through the edge slots 4.

This outward and downward movement causes the edge slots 4 to become smaller in the vertical plane and the diagonally opposite engaging edges 8 and 9 bite opposite sides of the bar in proportion to the applied pressure. Second, the sides of the edge slots 4 being perpendicular to the faces of the clip and the legs 7 being bent so as to form an angle of or near 45° with the bar passing through the edge slots 4 it will be seen, as most clearly shown in Fig. 4, that the diagonally opposite engaging edges 8 and 9 are a maximum for efficiency, by referring to Fig. 4, it will also be seen that by the above novel construction and combination of parts that the bar need only touch the diagonally opposite engaging edges 8 and 9 and in this manner there is nothing to hinder the force, due to the spring in the clip, to rest anywhere except upon the diagonally opposite engaging edges 8 and 9 and this is sufficient to cause the diagonally opposite engaging edges 8 and 9 to bite opposite sides of the bar.

25 To place a spring clip upon a member all that is necessary is to squeeze the legs 7 together and slip the spring clip upon the bar, as bar 1, so that it passes through the edge slots 4, on releasing the pressure upon the legs 7 the clip springs into a position so that the diagonally opposite engaging edges 8 and 9 are firmly pressed against opposite sides of the member or bar passing through the edge slots 4. This secures the bar 2 from moving along the bar 1, but the clip and bar 1 are free to move along bar 2. To eliminate this movement I employ another of my spring clips and apply it to bar 2 as shown in Fig. 1. This secures both bars 30 in their proper places.

The above description applies equally to the spring clip 3 shown in Fig. 2 and the modified construction shown in Fig. 3 wherein in the spring clip 3' shows the central cross groove 5' for bars of rectangular dimensions.

45 It will be noted that various changes may be made in the details of construction without departing from the spirit and scope of the invention.

50 What I claim and desire to secure by Letters Patent is—

1. In a reinforced construction, the combination of cross members or bars with spring clips having central cross grooves, 55 to receive the members or bars and partly surround same, resilient arms extending outward and downward from the edges of the central cross grooves and terminating in legs bent upward from the backs of the resilient arms; said legs provided with edge slots that receive the coöperating cross members or bars and form seats for same, substantially as specified.

60 2. In a reinforced construction, the combination of cross members or bars with

spring clips having central cross grooves to receive the members or bars and partly surround same, resilient arms extending outward and downward from the edges of the central cross grooves and terminating in 70 legs bent so as to form angles of or near 45° with the coöperating members or bars, said legs provided with edge slots that receive the members or bars and form seats for same, substantially as specified.

3. In a reinforced construction, the combination of cross members or bars with spring clips having central cross grooves to receive the members or bars and partly surround same, resilient arms extending outward and downward from the edges of the central cross grooves and terminating in 80 legs bent so as to form angles of or near 45° with the coöperating cross members or bars, said legs provided with edge slots whose 85 sides are perpendicular to the faces of the clips opposite engaging edges that bite opposite sides of the coöperating cross members or bars and prevent them from slipping through the edge slots; said engaging edges 90 formed by the sides of the edge slots being perpendicular to the faces of the clips and the legs carrying said edge slots bent so as to form angles of or near 45° with a horizontal plane passed through the central 95 cross groove, substantially as specified.

4. In a reinforced construction, the combination of cross members or bars with spring clips having central cross grooves to receive the members or bars and partly surround 100 same, resilient arms extending outward and downward from the edges of the central cross grooves, so as to form resilient body portions for the legs and space between said legs to permit the clips to intersect, said legs 105 provided with edge slots that receive the coöperating cross members or bars and form seats for same substantially as specified.

5. In a reinforced construction, the combination of coöperating cross members or 110 bars with a pair of spring clips struck from a blank sheet or plate of steel, or other resilient metal, and crimped so as to form central cross grooves to receive the coöperating cross members or bars and partly inclose 115 same, resilient arms extending outward and downward from the top edges of the central cross grooves, legs formed by the extremities of the resilient arms being bent upward from the backs of the clips so as to form angles of or near 45° with a horizontal plane 120 passed through the central cross grooves, said legs provided with edge slots whose sides are perpendicular to the faces of the clips, and diagonally opposite engaging 125 edges that bite opposite sides of the coöperating cross members or bars and prevent them from slipping through the edge slots, said engaging edges formed by the sides of the edge slots being perpendicular 130

to the faces of the clips and the legs carrying said edge slots bent so as to form angles of or near 45° with a horizontal plane passed through the central cross grooves, 5 said clips interlocked so that the central cross groove of one clip receives one of the coöperating cross members or bars and the central cross groove of the other clip to receive the other coöperating cross member or 10 bar and the edge slots of one clip to receive the member or bar that passes through the central cross groove of the other clip and the edge slots of the other clip to receive the member or bar that crosses the member or 15 bar passing through its central cross groove, substantially as specified.

6. In a spring clip for the coöperating cross members of a reinforced construction the combination of a central cross groove, to 20 receive one of the coöperating cross members and partly encircle same, with resilient arms, extending outward and downward from the top edges of the central cross groove, so as to form resilient body portions 25 and space on each side of the central cross groove so a like clip can be used in combination to interlock the coöperating cross members, the extremities of said resilient arms bent upward from the back of the clip so 30 as to form angles of or near 45° with a horizontal plane passed through the central cross groove, said extremities provided with edge slots having diagonally opposite engaging edges that secure the member passing 35 through the edge slots by biting opposite sides of same, substantially as specified.

7. In a spring clip for the coöperating cross members of a reinforced construction, the combination of a central cross groove, to 40 receive one of the coöperating cross members and partly encircle same, with resilient arms extending outward and downward from the top edges of the central cross groove, so as to form resilient body portions and space on 45 each side of the central cross groove so a like clip can be used in combination to interlock the coöperating cross members, the extremities of said resilient arms bent upward from the back of the clip, said extremities 50 provided with edge slots to receive the other coöperating cross member, said edge slots provided with diagonally opposite engaging edges formed by the sides of the edge slots

being perpendicular to the faces of the clips and the extremities carrying said edge slots 55 bent so as to form angles of or near 45° with a horizontal plane passed through the central cross groove, substantially as specified.

8. In a spring clip for the coöperating cross members of a reinforced construction, having a central cross groove to receive one of the coöperating cross members and partly encircle same, resilient arms extending outward and downward from the top edges of the central cross groove so as to form resilient body portions and space on each side of the central cross groove so a like clip can be used in combination to interlock the coöperating cross members, the extremities of 60 said resilient arms bent upward from the back of the clip so as to form angles of or near 45° with a horizontal plane passed through the central cross groove, said extremities provided with edge slots having 65 diagonally opposite engaging edges, the resilient arms, substantially as specified. 70

9. In a spring clip for the coöperating cross members of a reinforced construction, having a central cross groove, to receive one of the coöperating cross members and partly encircle same, resilient arms extending outward and downward from the top edges of the central cross groove so as to form resilient body portions and space on each side of the central cross groove so a like clip can be used in combination to interlock the coöperating cross members, the extremities of 80 said resilient arms bent upward from the back of the clip so as to form angles of or near 45° with a horizontal plane passed through the central cross groove, said extremities provided with edge slots having 85 diagonally opposite engaging edges, the resilient arms, substantially as specified. 90
